FLUSH TYPE DOOR LOCK

Albert L. Pelcin, Maple Heights, Ohio, assignor to
The Eastern Malleable Iron Company, Naugatuck, Conn., a corporation of Connecticut

Application March 14, 1951, Serial No. 215,517

1 Claim. (Cl. 292—173)

1

This invention relates to locks of the type installed substantially as indicated by the which occupy a substantially flush position when installed in a recess or opening of an external surface of a door or the like and which, although applicable to various uses, are particularly suitable for the doors of utility trucks and other automotive vehicles because they normally do not have any projecting part likely to cause personal injury.

As one of its objects this invention aims to provide an improved flush type door lock of a unitary construction adapted to be quickly and easily installed, and which comprises a relatively small number of parts adapted to be economically produced and assembled.

Another object is to provide a unitary door lock of this character having a body member in the form of a shallow recessed sheet metal pan and an actuating handle adapted to swing outwardly and inwardly of such pan recess and being of a size and shape to form a partial cover for the pan recess, and in which a guideway for the bolt of the lock is formed by a hollow member located on the back of the pan and secured directly to the bottom wall thereof.

A further object is to provide an improved flush type door lock of the character mentioned in which a spring-pressed bolt is retained in the guideway by an arm projecting from the back of the actuating handle and extending into the guideway through an opening of the bottom wall of the pan-shaped body member.

Still another object is to provide an improved flush type door lock of the character mentioned in which the pan-shaped body member and the actuating handle have openings which are in substantially aligned relation when the handle is in a retracted position in the recess of the body member and in which a locking device mounted on the body member includes a key-actuated bolt which is engageable in the aligned openings.

The invention can be further briefly summarized as constituting in certain novel combinations and arrangements of parts hereinafter described and particularly set out in the claim hereof.

In the accompanying sheet of drawings,

Fig. 1 is a front elevation showing the improved lock installed in substantially flush relation in a recess or opening of an external door surface;

Fig. 2 is a longitudinal edge view of the installed lock and also showing adjacent portions of the door and door frame in section;

Fig. 3 is a transverse section taken through the

2

Fig. 4 is a longitudinal section taken through the installed lock substantially as indicated by the horizontal section line 4—4 of Fig. 1. The improved door lock 10 is shown in the accompanying drawing as comprising, in general, a recessed body member 11 slidably supporting a bolt 12 which is adapted to be extended by a compression spring 13 and an actuating handle 14 operable to retract the bolt against the action of the spring.

The lock 10 can be used in various different locations and for various purposes, but is especially suitable for use on the doors of automotive vehicles and particularly on the doors of tool compartments or the like of utility trucks. As one example of such use, the improved lock 10 is shown in the drawing as having been installed in an opening or recess 15 of the front or external surface 16 of a door 17 which is used to close a tool compartment or the like of such a utility vehicle. As here illustrated, the door 17 is mounted to swing on a vertical pivot axis provided by suitable hinges (not shown) and in its closed position cooperates with adjacent vehicle structure such as the door frame 18. A striker plate 19 mounted on the door frame 18 is provided with an opening 20 into which the bolt 12 extends when the door 17 is in its closed position.

The body member 11 of the improved lock 10 comprises a substantially pan-shaped sheet metal part having a substantially flat bottom wall 21 and pairs of opposed side and end walls 22, 23 and 24, 25 defining a shallow pan-like recess 26. The recess 26 is of a quadrangular shape having rounded corners 26a and extends into the body member 11 from the front thereof and is preferably of a substantially uniform depth. The body member 11 also includes a laterally extending integral flange 27 which is substantially continuous around the perimeter of the recess 26 and extends in an outturned relation thereto. For a purpose to be further explained hereinafter, the portion of the flange 27 which extends along the side 23 of the body member 11 is a substantially triangular relatively wide flange portion 27a having an opening 28 therein.

A hollow guide member 30, preferably formed of sheet metal, is directly connected with the body member 11 and defines a guideway 31 in which the bolt 12 is slidable. The guide member 30 is here shown as having a channel-shaped intermediate portion of a substantially quadrangular cross-sectional shape defining the guideway 31.

and a pair of oppositely extending integral longitudinal flanges 32 and 33. The guide member 30 is connected with the body member 11 by having the flanges 32 and 33 secured against the flat rear surface of the bottom wall 21 as by means of spot welding 34.

The bolt 12 comprises a bar or the like of a substantially quadrangular cross-sectional shape corresponding with that of the guideway 31 and is longitudinally slid able in the latter. The bolt is provided with a substantially flat end face 35 at the inner end thereof and at its outer end is provided with a convexly curved portion 36 for cooperation with the striker plate 19.

The compression spring 13 is located in the guide member 30 in engagement with the inner end 35 of the bolt 12 and applies outward thrust to the bolt tending to project the same from the guideway 31. The spring 13 also seats against an end wall provided at the inner end of the guide member 30 and formed by an integral portion 38 of the latter which is bent to a substantially right angle relation across the end of the guideway as shown in Figs. 3 and 4. The angularly bent portion 38 is held against outward bending as by means of a pair of in-turned lugs 39 formed by integral portions of the side walls of the guide member.

The bolt 12 is provided with a longitudinal slot 40 extending into the bolt from the flat face thereof which lies against the bottom wall 21 of the body member 11. As shown in Fig. 4, the bottom wall 21 is also provided with a longitudinal slot 41 which is in substantially registering relation with a portion of the slot 40 of the bolt. The handle 14 carries a rigid bolt-actuating arm 42 having a blade portion 43 which extends through the slot 41 into the guideway 31 and engages in the slot 40 of the bolt. The arm 42 is preferably in the form of a sheet metal member and includes a substantially flat attaching portion 44 which is secured to the handle 14, as by means of spot welding 45, such that the blade portion 43 extends rearwardly from the handle at the back thereof.

The handle 14 is preferably made of sheet metal and comprises a generally quadrangular substantially flat plate portion 46 adapted to form a cover for a portion of the recess 26 of the body member 11. The handle 14 also includes a pair of in-turned integral flanges 47 and 48 along the sides thereof and which lie adjacent the longitudinal side walls 22 and 23 of the body member 11.

The handle 14 is pivotally connected with the body member 11 as by means of rivets or the like 49 and 50 which extend through the flanges 47 and 48 of the handle and through the side walls 22 and 23 of the body member. As shown in Figs. 1 and 4, the pivot members 49 and 50 are located adjacent the left edge of the handle member 14 such that this member is adapted to swing outwardly and inwardly with respect to the pan-shaped recess 26 of the body member. The drawing shows the handle 14 in its retracted position in which its outer surface is substantially flush with the door surface 16 and in which the handle forms a cover for the left end portion of the recess 26. The arm 42 is mounted on the handle 14 adjacent the pivoted edge thereof such that the arm and handle assembly forms a bellcrank lever for actuating the bolt 12.

The transverse inner end wall 51 of the slot 40 of the bolt 12 forms an abutment surface with

which the blade portion 43 of the actuating arm 42 cooperates. When the handle 14 is grasped by the insertion of the fingers through the open right end portion of the recess 26 and is manually swung outwardly of this recess, the blade portion 43 applies inward thrust to the abutment surface 51 and retracts the bolt 12 into the guideway 31 in opposition to the spring 13. Such withdrawal of the bolt into the guideway disengages the same from the opening 20 of the striker plate 19 to permit opening movement of the door 17.

When the handle 14 is released, the spring 13 moves the bolt 12 outwardly causing the abutment surface 51 to apply thrust to the blade portion 43 in a direction to swing the handle inwardly of the recess 26 to its substantially flush position shown in the drawing. Thus with the lock construction above described, it will be seen that the handle 14 will be held in a substantially flush position by the action of the spring 13 at all times except when the handle has been manually swung out of the recess 26. This normally flush position for the handle 14 is very desirable because the handle then cannot be left in a projecting position in which it might cause personal injury by striking a pedestrian.

As another feature of the improved door lock 10, a key-actuated locking device 52 is provided on the wide flange 27a of the body member 11 and cooperates with the handle 14 for locking the same in its initial or retracted position. The locking device 52 may comprise a conventional cylinder type lock unit adapted to be controlled and actuated by a conventional key 54 when inserted thereto. The cylinder unit 53 is mounted on the flange 27 by being disposed in the opening 28 and retained in such position by the nut 55. The locking device 52 also includes a swinging bolt 56 which is connected with the inner end of the cylinder unit 53 to be swung thereby.

As shown in the drawings, the side wall 23 of the body member 11 is provided with a locking slot 57 and the adjacent flange 48 of the handle 14 is also provided with a locking slot 58 which is in substantially registering relation with the slot of the body member when the handle is in its retracted position. When the locking device 52 has been assembled on the flange 27a of the body member 11, the bolt 56 will occupy a position such that rotation of the cylinder member 53 in one direction by the key 54 will swing the bolt into the aligned slots 57 and 58 to lock the handle 14, and rotation of the key in the opposite direction will swing the bolt 56 out of such slots to unlock the handle.

As shown in Fig. 4, the slot 40 of the bolt 12 is made of a length such that the bolt will be movable into the hollow guide member 30 in opposition to the spring 13 whenever the door 17 is slammed shut and this inward movement of the bolt can take place without causing an outward swinging of the handle 14. Thus the increased length of the slot 40 provides a separable operating connection between the arm 42 and the abutment surface 51 which will permit the door 17 to be slammed shut even though the handle is locked in its retracted position by the locking device 52.

When the improved door lock 10 is assembled on the door 17, the pan-like portion of the body member 11 engages in the recess or opening 15 of the door and the outturned lateral flange 27 of the body member forms a locating flange which

overlies a portion of the front surface 16 in substantial flush relation thereto. The lock is retained in this assembled relation on the door by means of screws or any other suitable connecting devices (not shown).

From the accompanying drawing and the foregoing detailed description it will now be readily understood that this invention provides an improved door lock which is of a very simple construction embodying a relatively small number of parts, and when installed on the door of an automotive vehicle occupies a substantially flush position such that there will be no projecting part or parts likely to cause accidental personal injury. Moreover, it will be seen that this improved door lock is of a unitary construction in which the actuating handle normally occupies a retracted position in the recess of the body member and in which a hollow guide member for the sliding bolt is connected with the body member by being mounted directly on the rear surface of the bottom wall of the body member. Additionally, it will be seen that a key-actuated locking device is provided and cooperates with the body member and the handle in a novel manner for maintaining the handle in a locked condition when desired.

Although the improved door lock of this invention has been illustrated and described herein to a somewhat detailed extent, it will be understood of course that the invention is not to be regarded as being limited correspondingly in scope, but includes all changes and modifications coming within the terms of the claim hereof.

Having thus described my invention, I claim:

In a lock intended for substantially flush installation in a surface opening of a door, a sheet metal body member of substantially quadrangular pan-like shape having side walls and a substantially flat bottom wall defining a recess of substantially uniform depth extending into said body member from the front thereof, said body member also having a substantially continuous lateral flange extending around the front recess thereof and engageable with the door surface, a substantially channel shaped sheet metal guide member having lateral flanges secured to said bottom wall and mounting said guide member on the back of said body member for defining a longitudinal guideway thereon, said bottom wall having a longitudinal slot therein connecting said

recess with said guideway, a bolt slideable in said guideway and having a slot therein substantially in register with the slot of said bottom wall, a spring in said guideway engaging said bolt, a handle comprising a substantially quadrangular sheet metal plate member disposed in said recess and being of a plan size to form a cover for a portion of said recess with one end of said handle spaced from one end of said recess to permit insertion of the fingers therebetween, said handle having a pair of inturned integral flanges thereon extending into said recess adjacent a pair of the side walls of said body member, pivot means connecting said flanges with said pair of side walls adjacent the other end of said recess for swinging of said handle outwardly and inwardly of said recess, and a sheet metal arm rigidly connected with said handle and having a blade portion extending rearwardly from the handle through the slot of said bottom wall into said guideway and engaging in the slot of said bolt, said spring being effective to extend said bolt from said guideway and to cause swinging of said handle inwardly of said recess to a retracted position therein and said arm being effective on said bolt for retracting the latter against said spring in response to manual swinging of said handle outwardly of said recess, the slot of said bolt being of a length such that a portion thereof forms a clearance space for said arm which permits inward movement of said bolt in opposition to said spring while said handle remains in its retracted position in the recess of said body member.

ALBERT L. PELCIN.
